UNITED STATES PATENT OFFICE.

JOHN T. OBENCHAIN, OF LOGANSPORT, INDIANA.

GRADUAL-REDUCTION MILL.

SPECIFICATION forming part of Letters Patent No. 308,978, dated December 9, 1884.

Application filed May 19, 1884. (No model.)

To all whom it may concern:

Be it known that I, JOHN T. OBENCHAIN, of Logansport, Cass county, Indiana, have invented certain new and useful Improvements 5 in Gradual-Reduction Mills, of which the following is a specification.

This invention relates to the general arrangement of parts in a gradual-reduction mill, whereby the various steps in the gradual-re- 10 duction processes are executed in practically a single machine.

In my improved grinding-mill the grain is fed to a machine of comparatively small dimensions, and alternately subjected to all of 15 the various processes involved in gradual reduction.

The invention will be readily understood from the following description, taken in connection with the accompanying drawings, in 20 which—

Figure 1 is a side elevation of a machine embodying my improvements, the chop-grader nearest the spectator being omitted; Fig. 2, a plan of the same, the chop-grader referred to 25 also being omitted in this case; Fig. 3, a vertical section through one of the leg-spouts, and Fig. 4 a side elevation of the lower portion of one of the legs.

In the drawings, A represents a husk containing a grinding-mill adapted for the simultaneous performance of several different finenesses of grinding, as hereinafter more fully specified; B, the driving-pulley upon the vertical spindle of the machine; C, the legs supporting the husk; D, spouts formed within the legs, and leading from the separate grinding-chambers of the husk; E, flange-joints at the outer ends of the leg-spouts, by which connection is made with those spouts; F, upwardly-facing lugs near the feet of the legs provided for the purpose of supporting the chop-graders; G, a bridge-tree attached to the legs, and supporting the usual step bearing for the spindle of the grinding-mill; H, an ordinary silent 45 feeder by which the grain is fed to the initial element of the grinding-mill; I, a feed-spout leading from the silent feeder to the first grinding-chamber of the grinding-mill; J, the leg-spout leading from the first grinding-chamber 50 of the grinding-mill into the base of the elevating chop-grader K, which is omitted from

the drawings for the purpose of exposing matter to the rear of it; L, a funnel leading to the second grinding-chamber of the grinding-mill, and adapted to receive its supply of material 55 from the chop-grader at K; M, the leg-spout leading from the second grinding-chamber to the foot of the second chop-grader; N, the second chop-grader, receiving its supply through the leg-spout M and carrying it upward to 60 the point of discharge above the grinding-mill; O, the discharge-spout of the chop-grader N, leading downward to the grinding-mill; P, the receiving-funnel of the third grinding-chamber 65 of the grinding-mill, receiving material through the discharge-spout O; Q, leg-spouts similar to the spout M, successively arranged around the mill; R, successive chop-graders; S, discharge-spouts from the tops of the successive 70 chop-graders to appropriate grinding-chambers of the grinding-mill; T, the receiving-funnels for the successive grinding-chambers of the grinding-mill; U, the final chop-grader, receiving its supply from the final grinding-chamber of the grinding-mill; V, the discharge-spout of the final chop-grader; W, a shaft 75 formed by an upward prolongation of the central spindle of the grinding-mill, adapted to operate the silent feeder, but prolonged still farther upward; X, a pulley upon the upper end of the shaft W; Y, pulleys at the tops of the central shafts of the top graders; Z, a housing-spider furnishing top bearings for the shafts of the chop-graders, and also the shaft W; a, a gimble-bearing at the top of the main 80 spindle of the grinding-mill, and b the husk-floor of the grinding-mill.

The grinding-mill consists of a central grinding-roll provided with a circumferential series of opposing grinding agents each inclosed 85 in a separate chamber within the husk, and each provided with its own inlet and outlet, each successive grinding agent being so arranged as to yield a product finer than its predecessor. Such a mill as this may be found 90 fully described in Letters Patent No. 289,695, granted to me December 4, 1883, for an improvement in grinding-mills, and also in an application (Serial No. 128,247) for Letters Patent filed by me April 17, 1884, for improvements in grinding-mills.

The chop-graders receive their supplies at

their bases, sift the material passing through them, elevate the material while it is being sifted, discharging the finer products through the bottom outlets, and discharging the coarse product at their tops, to be reground. Chop-graders of this kind will be found fully described in an application (Serial No. 132,001) for Letters Patent filed by me May 19, 1884, for improvements in chop-graders.

10 The grinding-mill is driven by a belt upon pulley B. The upper shaft, W, operates the silent feeder, which is of ordinary construction, and also drives the central pulley, X. The belt from pulley X operates all of the pulleys Y, as indicated, and consequently all of the chop-graders, though, if preferred, a series of belt-pulleys may be applied at X and each of the chop-graders be driven by a separate belt.

15 The chop-graders are supported vertically by the lugs F, projecting from the legs, and they are secured in position by the bolts securing the flange-joints E. Their tops are steadied by the spider Z. The chop-graders thus, while surrounding the grinding-mill, do not 20 encumber it or prevent convenient access to it by reason of interfering attachments. The system of conduits is extremely simple, and each individual conduit is extremely short and direct.

20 The operation of the mill is as follows: The silent-feeder spout I discharges into that chamber of the grinding-mill which yields the coarsest product, and each successive chamber moving to the right, as viewed in Fig. 30 2, yields a product of increasing fineness, and the final chamber from which the chop-grader U receives its supply yields a product representing the completion of the gradual-

reduction process of grinding. Grain enters the silent feeder, thence by the spout I it goes 40 to the first chamber and receives its first breaking, thence through spout J from this first chamber to the foot of the first chop-grader, which occupies the position K. This chop-grader sifts out the fine material and 45 discharges it, elevates the coarse material and discharges it into the next grinding-chamber, where it is subjected to a finer action, and is then passed successively around through chop-graders and grinding-chambers alternately 50 until it reaches the final chop-grader U, where it is discharged at the spout V.

It will be understood, of course, that the real product of the machine is that material which has been sifted out by the chop-graders, 55 and that the final discharge at the spout V will amount to little or nothing.

This machine is simple, strong, self-contained, and efficient. It is capable of a result not attainable by any known machine or system of machinery capable of being operated 60 in less than five times the space required by this machine.

I claim as my invention—

The combination of a gradual-reduction 65 grinding-mill constructed with independent reducing-chambers, a circumferential series of chop-graders secured thereto, and conduits between the grinding-chambers and the chop-graders, whereby the grain is subjected to a 70 series of alternate reductions and separations, substantially as set forth.

JOHN T. OBENCHAIN.
